UNITED STATES PATENT OFFICE.

JOHN McGOLDRICK, OF BALTIMORE, MARYLAND.

LIFE-BOAT AND LAUNCHING MECHANISM THEREFOR.

1,134,630.

Specification of Letters Patent.

Patented Apr. 6, 1915.

Application filed July 23, 1913. Serial No. 780,726.

To all whom it may concern:

Be it known that I, JOHN McGOLDRICK, a citizen of the United States of America, and a resident of the city of Baltimore, State of Maryland, have invented certain new and useful Improvements in Life-Boats and Launching Mechanism Therefor, of which the following is a specification.

This invention relates to certain improvements on the device shown and described in my U. S. Patent #1,022,432, granted to me April 9, 1912, the object thereof being to provide means by which the removable boat-cover shown in that application may be in the form of and used itself as a boat or raft. For this purpose it comprises a boat-cover in the form of a boat or raft, which when in place upon the boat is inverted. With it I employ proper securing means to hold it in place, together with proper releasing mechanisms, the securing means and releasing mechanism being of the general type shown in my prior patent.

It further comprises means by which such cover-boat may, after the lowering of the main boat, be turned to its erect position and lowered, all by the aid of the falls by which the main boat itself is handled.

Referring to the accompanying drawings, in which corresponding parts are designated by corresponding marks of reference,—

Figure 1 is an in-board elevation of a boat having my invention applied thereto; Fig. 2 is a vertical transverse section on the lines X²—X² of Fig. 1. Fig. 3 is an enlarged fragmental view of certain parts shown in Fig. 2. Fig. 4 illustrates in half section and in end view, respectively, the cover-boat in the position it assumes when turned over, and ready for lowering. Fig. 5 is a fragmental side elevation of the cover-boat in its inverted position. Fig. 6 is a corresponding view of the cover-boat in its erect position. Fig. 7 is a fragmental plan view of the end of the cover-boat in erect position.

The main boat 1 when swung in-board, rests on a plurality of pivoted chocks 2, each of which is locked erect by an eccentric 14 fast on a corresponding shaft 13^a, mounted in the chock-block as in my prior application. The shafts 13^a project from side to side of the main boat beneath the same, and each has rigidly secured to one end thereof, an arm 13 the upper end of which projects through vertical slots formed in the outer edge of the gunwale 3 of the main boat, and above such gunwale having locking holes

formed therein project, when the cover-boat is in place, the spring-pressed bolts 9 carried by the latter. These spring bolts are 60 adapted to be retracted for the purpose of releasing the gripes formed by the arms 13, by latches 4 pivoted in the cover-boat and having shoulders 4^a thereon which engage the inner lower edge of the gunwale 3 of the 65 main boat. The lower end of these latches are connected to halyards 20 which pass through fair-leaders 20^b secured on the cover-boat. Thus the shoulders 4^a upon the latches 4 when the cover-boat is in place, 70 afford means for securing such cover-boat to the main boat while the bolts not only hold the cover-boat in place upon the main boat, but by their engagement with the arms 13 lock the main boat down upon the chocks. 75 In order to accommodate the arms 13, to boats of different depths, such lever arms are preferably formed in two parts 13^c and 13^d united by a slot and pin connection which may be adjusted and set when so ad- 80 justed. The positions of the arms 13 in respect to the vertical is such that when the arms are released from the boat-cover, they will fall by gravity, throwing up their eccentric and releasing the boat-chocks and 85 leaving them free to fall upon the initial movement of the boat. The connection be- 90 tween the members 13^c and 13^d is the usual bolt and pin connection in which the bolt is adjusted and clamped at any point in the slot in the member 13^d, the pin portion of the connection being pivoted in the member 13^c, thus permitting the lower members 13^d of the arms to fall in arc of circles, and withdraw the upper members from the apertures 95 in the boat gunwales.

Between the davits 15 on which the boat is swung is mounted a spreader 16 and the releasing ropes 30 of the cover-boat pass through proper pulleys and fair-leaders 100 upon the spreader and davits to a suitable winch 31 upon each of the davits, there being one of these boat-releasing ropes 30 at each end of the boat, each of such ropes having the hook 30^a caught in the bight of the 105 corresponding releasing halyard 20.

The operation of launching the boat of the device as before described is substantially the same as that shown in my prior patent. In so launching the boat, the 110 winches are operated to slightly lift the cover-boat and to thereby place strain upon the boat-releasing ropes, whereupon the locking mechanism securing the cover-boat to

the main boat will be actuated to release the boat cover from the boat and to release the gripe structure. The arms 13 fall down by gravity, releasing the chocks and upon now 5 swinging the boat outward, the chocks will also fall, whereupon the main boat can be lowered in the usual way, leaving the cover-boat suspended by the boat-releasing ropes 30.

10 If the main boat is to be carried suspended from the davits, and the chocks and gripe structure are not used, the lowering of the main boat will place strain on the releasing halyards 20 which will retract the latches 4, 15 thus releasing the main boat and cover-boat. The former may be then lowered leaving the cover-boat suspended.

10 The cover-boat 32 itself is in the general form of a life-boat having blunt ends 20 formed by air-chambers 32^a at each end of a cock-pit.

Having reference to the cover-boat in its inverted position, on each of its side structures are gunwales 35 adapted when the 25 cover-boat is on the main-boat to lie upon the outside of the main-boat gunwales 3 and having at each end a projecting lip 31^a which projects over the covers 3^a of the fore and aft air chambers of the boat, thus effectually sealing and closing in such boat. The 30 releasing halyards 20 may pass through suitable apertures formed in such projecting lips. The coaming 31^b of the cock-pit of the cover-boat extends below the gunwales 35 of the cover-boat, the space intermediate of the two being covered as is usual in boat-construction. The locking structure comprising the bolts and latches are fastened to the fore and aft coaming of the cock-pit and 40 thus no apertures are necessarily formed in the walls of such cock-pit, or in the air-chambers at the ends thereof. To avoid this, the air-chambers themselves may have depressions 32^b formed in their lower walls 45 to receive the pivotal points of the latches. Within the cock-pit of the cover-boat may be properly secured the equipment desired or required for the navigation of the cover-boat, which may also possess other constructional features common to life boats.

50 To suitable points on opposite sides of the center and on the upper faces of the fore and aft tanks 32^a (considering the cover-boat in erect position) suitable eyes 33 are secured through which pass the links 34, the upper ends of which engage such eyes by 55 elongated loops 34^a, while the upper ends of the two links on the corresponding ends of the cover-boat are each received by a ring 34^b, to which is swiveled a second ring 34^c. In the normal position of the parts with the 60 cover-boat upon the main-boat, the links may be lightly lashed against the under sur-

face of the air tank wall as shown in Fig. 5. With this construction after the main boat 65 has been lowered the falls 36 may be again hoisted and the hooks 36^a thereof caught in the rings 34^c of the cover-boat. As shown in Fig. 5, the elongation of the loops of these links permit the links to be normally 70 shoved back inside of the ends of the cover boat to permit the latter to properly set upon the main boat, but when the rings thereon are to be engaged by the fall hooks the links may be drawn forwardly, as shown in dotted 75 lines in Fig. 5. If now, the hooks 31^a of the cover-releasing ropes are released from the halyards 20, the cover-boat will be swung entirely from the boat falls. Inasmuch as the points of supports formed by eyes 16^a 80 are below the center of gravity of the cover-boat, the latter is in unstable equilibrium, and can or will be readily turned over to assume the position shown in Fig. 4, and being suspended from the falls, the cover-boat may 85 be now lowered and used as a boat.

Having thus described the invention what I claim as new and desire to secure by Letters Patent is:—

1. The combination with a main boat, of 90 a cover-boat forming a cover therefor when in inverted position, means for locking the cover-boat and main boat together, means for releasing such locking means, and means for then lowering the main boat and the 95 cover-boat.

2. The combination with a main boat, of 100 a cover-boat forming a cover therefor when in inverted position, means for lowering the main boat and simultaneously suspending 100 the cover boat, and for then turning over the cover-boat and lowering it.

3. The combination with a main-boat, of 105 a cover-boat forming a cover therefor when in inverted position, a lock between the main boat and the cover boat, means for suspending the cover-boat in inverted position, means for lowering the main boat, and for then turning over the cover-boat and lowering 110 it.

4. In a boat-securing device, the combination with pivoted chocks, a shaft having an eccentric thereon forming a lock for such chocks, an extensible lever integrally secured to such shaft having a pivoted extension, 115 apertures in the boat gunwales receiving the pivoted extensions of the levers, and means located above the gunwales for engaging such pivoted extension.

In testimony whereof I hereunto affix my 120 name in the presence of witnesses.

JOHN McGOLDRICK.
